UNITED STATES PATENT OFFICE.

FRED E. BURLINGAME, OF PAWTUCKET, RHODE ISLAND, ASSIGNOR TO ATTLEBORO BRAIDING CO., OF SOUTH ATTLEBORO, MASSACHUSETTS, A CORPORATION OF MASSACHUSETTS.

LACING-TIPPING MACHINE.

Application filed June 26, 1924. Serial No. 722,531.

This invention relates to an improved apparatus for forming tips on lacings such as shoe lacings, corset lacings and the like; and the object of this invention is to provide in 5 such a machine or apparatus, means for feeding the lacing into position to form the tips thereon and to remove the lacing from the tipping means after having been tipped.

A still further object of the invention is 10 to provide means including a plurality of sets of tipping devices and to provide means whereby the lacing is presented successively to these different tipping devices to have tips formed thereon at intervals along its length. 15 My invention further consists in the provision of means for applying cement to portions of the lacing at intervals along its length and to deposit stiffening core members into the treated portion of the lacing 20 about the core to form tips at intervals along the length of the lacing.

A still further object of the invention is to provide means for drying the cement on the lacing tip while being formed.

25 My invention further consists in the provision of means for severing each length of the lacing and removing the lacing from the tip-forming means after the cement has become set.

30 With these and other objects in view, the invention consists of certain novel features of construction, as will be more fully described, and particularly pointed out in the appended claims.

35 In the accompanying drawings:

Figure 1 is a plan view of my improved tipping apparatus.

Figure 2 is a side elevation showing my improved tipping apparatus.

40 Figure 3 is a detail illustrating the mechanism by which the core members are received from a hopper and deposited one at a time into the cement-treated portions of the lacing.

45 Figure 4 is a detail illustrating the means for operating the ratchet feed for successively depositing the core members on the cement-treated portions of the lacing.

Figure 5 is an enlarged view illustrating 50 the cement nozzle as depositing cement on the lacing which has been formed into crescent shape in cross section to receive the cement and subsequently the core before the final folding or wrapping operation.

55 Figure 6 is a detail illustrating the means

for opening the different valves along the cement receptacle for depositing cement on a plurality of lacing strands as they are being drawn into the machine to have tips formed thereon at intervals along their 60 lengths.

Figure 7 is a top view of one of the die blocks partly broken away to show the set of cooperating tip forming dies therein.

Figure 8 is a sectional side elevation of the 65 die block with the tip-forming dies therein.

It is found in practice of advantage to be able to feed a lacing fabric continuously to the dies to form tips at intervals along its length, and to provide means whereby the 70 tip after having been formed on the lacing may be released and the lacing with its finished tip removed, all automatically.

It is also found of advantage to provide means whereby a number of the lacings may 75 be operated upon simultaneously to form tips on each and so materially increase the production of the machine; and the following is a detailed description of the present embodiment of my invention in which one 80 means is shown by which these advantageous results may be accomplished:—

In order to provide means for automatically feeding the lacings to the dies, to be tipped and after having been formed to remove the lacing from the dies, I have provided a drum 10 which is mounted upon a shaft 11 to be rotated slowly or at any predetermined speed from a motor (not shown) through a pulley 12, shaft 13, pulley 14, belt 85 90 15, pulley 16, shaft 17, cone 18, cone belt 19, cone 20, shaft 21, belt 22 onto large pulley 23, the speed at which this drum is driven being varied by moving belt guide 24 along the bar 25 to adjust the belt 19 on the cone 95 pulleys 18 and 20 and so regulate the speed of the drum as desired.

Any suitable means for forming tips on the lacings, may be employed and mounted about the circumference of the drum, but I 100 preferably employ a set of tip-forming dies 26 mounted in the die block 27, one pair of the dies 26 being mounted upon a slide plate 28 and operated by a lever 29, all as described in detail in my co-pending application Serial No. 719,299, Patent No. 1,592,422, granted July 13, 1926.

The die operating lever 29 is provided with a roll 30 which, as the drum revolves in the direction of the arrow, is caused to 110

engage a cam 31 fixed upon a cross bar 32, see Figure 1, between the frames 33, whereby the dies at a predetermined time of the revolution of the drum are caused to close 5 upon the lacings 34 to form a tip thereon.

In operating upon the lacings 34, each of which is led in from its respective reel 35, each of which is mounted on the shaft 36, these lacings are passed through a short section 10 of tubing 37, see Figure 5, which bends or shapes the lacing into substantially crescent shape in cross section and into this short section of tubing I extend the discharge end of a nozzle 38 which leads from the cement tank 39 through the valve 40, and on each of these valves I provide a stem 41 on which is mounted a lever 42 and all of these levers are connected up by a bar 43, one end of which is turned downwardly as 15 20 at 44 and is provided with a roll 45 which is arranged to contact with the cam 46 on the side face of the drum 10, whereby as the drum rotates the cam 46 is presented to the roll 45 and so opens all of the valves 40, 25 simultaneously, to deposit a given amount of cement from the tank onto sections of the different lacings as fed through their respective tubes, the valves being closed by action of spring 83 when the cam has released 30 the bar. The cement in tank 39 is under pressure which may be formed by any suitable means such as air pressure through a pump 48, or by any other suitable means.

The valves are opened for a sufficient 35 length of time to permit the cement to flow onto the traveling lines of lacings, a distance equal to substantially double the length of a tip, after which the cement is shut off and this cement-treated portion is then advanced to a point beneath the magazine 49 which carries a supply of short lengths of core wire 50 which wire is fed in from a roll 51 by means of the feed rolls 52, which rolls are driven from the main shaft 11 through 40 45 a belt 53, pulley 54, and gears 55 whereby when a length of this wire is advanced to bring up against the wall 56 of the hopper, it is severed by means of the cutters 57 and is fed by gravity down through the hopper 50 to be selected one at a time by the toothed feed-roll 58 through action of the pawl and ratchet mechanism, best illustrated in Figure 3. This mechanism is operated by a pin 59 on the drum 10 which engages the dog 60 pivoted at 61 on the bracket 62 so that each time this dog is engaged by the pin it pulls down the pawl 63 through movement of rod 64 and arm 65 thereby feeding a short length of core wire 50 around through the guard tube 66 until the opening 67 is reached when the core wire is permitted to drop into the cement-treated portion of the lacing 36.

The dies 26 are now caused to close by 60 65 action of the lever 29 above described, there-

by causing the cutter 68 to sever the lacing and the double length of core, and the dies 27 to fold or wrap the cement-treated portion of the lacing about this core and to hold the lacing so folded during the rotation of the drum on which the die block is mounted until the cement is dried or hardened, which action is hastened by heat which is applied through an electric heater 69, see Figure 8, mounted in the body of the die block. 70 75

No means are herein shown for operating the cutters 57, but any suitable means may be employed for this purpose. Also the faces of the feed rolls 52 may be corrugated, as shown in Figure 1, to act upon and roughen the surface of the core wire as fed so as to cause the fabric of the lacing to more closely adhere thereto when wrapped around and cemented to its surface. 80

In order to maintain the lacing in curved 85 form in cross section while being positioned in the space 70 between the dies 26, I have supported a grooved member 71 on the standard 72 and on the drum just in front the die block 27 so that as the lacing is drawn 90 into this space it is retained in this curved condition during the time that the core section is deposited thereon, which curved condition also assists in the first operation of the dies in wrapping the fabric about the core. 95

After this short section of tip core is deposited on the cement-treated section of the lacing, the travel of the drum which is continuous now causes the roll 30 on each lever 39 to engage its fixed cam 31 which is supported above and in proximity to the drum thereby closing these tip-forming dies upon the lacing and as the cams are passed the dies remain during the travel of the drum until the oppositely-disposed set of cams 73 which are fixedly mounted on the bar 74 are engaged by the roll 30 which serves to move this lever 29 in the opposite direction thus separating the dies and permitting the severed end 75 of the tip to fall upon the traveling belt 76, which belt is driven from pulley 78 on the shaft 11 through pulley 79 and pulley 80 to run the belt in the direction of the arrow and so deposit the lacings as released from the dies into the receptacle 81 it being understood that the forward end 75 of the lacing upon being released by its block starts in the reverse direction towards the receptacle 81 while the opposite end is still retained in its die block until that too is released by engagement with the cam 73 which permits both the second end of the lacing which has already started to travel back, to fall upon the belt and also releases the forward end of the next length of lacing to fall upon the traveling belt and start in its reverse direction towards the receptacle 81. 100 105 110 115 120 125

Thus it will be seen that the operation is entirely automatic, the lacing being drawn 130

in from the reel 36 by the travel of the die block while its dies are closed upon the lacing to form a tip thereon, thus advancing another length of lacing into position to be engaged by the dies in the next succeeding block and so on, each set of dies forming a tip on the lacing as presented thereto.

I do not wish to be restricted to the employment of a drum on which to mount my tip-forming devices as any means for advancing or moving these die blocks may be employed; neither do I wish to be restricted to the exact form of dies or means for forming the tip as any suitable means may be employed for this purpose.

I have herein shown a plurality of strands of lacing as being operated upon to be tipped, simultaneously, but I do not wish to be restricted to operating upon any particular number of lacings at the same time, as one or any other desired number may be fed and simultaneously operated upon.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a lacing tipping machine, dies for compressing a portion of a lacing into tip form, and means for moving the dies bodily while retaining the tip to feed forward another length of lacing into position to be tipped.

2. In a lacing tipping machine, a die block, dies in each block arranged to compress a portion of a lacing into tip form, and means for moving said block when the dies therein are closed upon a lacing to advance another length of lacing to be tipped.

3. In a lacing tipping machine, a plurality of sets of dies, means for moving said dies relatively to compress a portion of a lacing into tip form, means for moving said dies bodily when closed upon a tip to feed another length of lacing into position to be tipped by another set of dies.

4. In a lacing tipping machine, a plurality of cooperating die blocks having dies arranged to close upon a lacing to form a tip thereon, means for advancing said blocks to act successively upon a continuous length of lacing fabric to form tips thereon and also feed another length to the next succeeding die.

5. In a lacing tipping machine, a plurality of cooperating die blocks, each having a pair of dies arranged to close upon a lacing tip to form a tip thereon, a movable support on which said blocks are mounted in spaced relation to be presented successively to the lacing, each to close and form a tip thereon,

the movement of each die block serving to draw in a length of lacing to be acted upon by the next succeeding die block.

6. In a lacing tipping machine, a plurality of sets of cooperating dies, each set having a pair of dies arranged to close upon a lacing tip to form a tip thereon, a movable support on which said sets are mounted in spaced relation to be presented successively to the lacing, each to close and form a tip thereon, the movement of each set serving to draw in a length of lacing to be acted upon by the next succeeding die block, and deposit said lacing after the tip has been formed thereon.

7. In a lacing tipping apparatus, a drum, die blocks spaced about the periphery of said drum, cooperating dies in said blocks, means for rotating said drum and closing the dies in the different blocks successively upon the lacing as presented thereto to form a tip thereon and also to feed the lacing forward to be presented to and operated upon at intervals by the succeeding dies.

8. In a lacing tipping apparatus, means for applying cement at intervals to the lacing each having dies arranged to close upon the cement-treated portions of the lacing to form a tip thereon, means for moving the blocks and presenting them successively to the lacing whereby the movement of each block also serves to feed a length of lacing forward to be tipped by the next succeeding block.

9. In a lacing tipping machine, means for applying cement at intervals to the lacing, a plurality of die blocks, a rotatable drum on which said blocks are mounted at intervals about its periphery, cooperating dies in said blocks, means for closing said dies upon the treated portions of the lacing to form tips thereon, the movement of said drum causing said closed dies to feed a length of lacing to the next following die.

10. In a lacing tipping machine, means for applying cement at intervals to the lacing, a plurality of die blocks, a rotatable drum on which said blocks are mounted at intervals about its periphery, cooperating dies in said blocks, means for closing said dies upon the treated portions of said lacing to form tips thereon, the movement of said drum causing said closed dies to feed a length of lacing to the next following die, and means for automatically removing the tipped lacing from said dies.

11. In a lacing tipping apparatus, means for treating the lacing at intervals with cement, means for depositing a stiffening core on the cement-treated portion of the lacing, and a set of dies for wrapping the treated portion about the core and severing the same.

12. In a lacing tipping apparatus, means for treating the lacing at intervals with cement, means for depositing short lengths of

a stiffening core on said treated portions, means for wrapping each treated portion about its core, and means for moving the wrapping means bodily while engaging the lacing to feed another length of lacing into position to be tipped.

13. In a lacing tipping apparatus, means for treating the lacing at intervals with cement, means for depositing short lengths of a stiffening core on said treated portions, a set of dies for wrapping each treated portion about its core, a cutter for severing the tip portion, means for moving the dies bodily while engaging the lacing, and means for removing the lacing from the dies after having been tipped.

14. In a lacing tipping apparatus, means for treating the lacing at intervals with cement, means for depositing short lengths of a stiffening core on said treated portions, a 20 rotatable drum, a plurality of sets of dies carried by said drum, means for operating said dies to wrap each treated portion of the lacing about its core, means for rotating said drum while the dies engage the lacing to 25 feed another length to the next succeeding pair of dies, and means for heating the dies to dry the cement while retained therein during the rotation of the drum.

In testimony whereof I affix my signature.

FRED E. BURLINGAME.
